UNITED STATES PATENT OFFICE.

WILLIAM H. BROWNELL, OF BROOKLYN, NEW YORK.

DESIGN FOR A PUFF-BOX.

SPECIFICATION forming part of Design No. 14,016, dated July 3, 1883.

Application filed May 24, 1883. Term of patent 7 years.

To all whom it may concern:

Be it known that I, WILLIAM H. BROWNELL, of Brooklyn, in the county of Kings and State of New York, have invented and produced a new and original Design for Puff-Boxes, of which the following is a full, clear, and exact description.

Reference is to be had to the accompanying photograph, forming part of this specification, 10 in which a perspective view of my newly-designed puff-box is shown.

The box A is made in the shape of a kettle-drum, the cover B of the box being made in representation of the head of the same, which 15 cover is to be used as a plaque for receiving paintings, &c. The box A rests upon a standard, D, provided with three curved arms, E, and three suitable legs, F, the arms being adapted to receive the box. In loops at the 20 upper ends of the arms E drumsticks G are held, the head ends of which are crossed, and appear to rest on the head of the kettle-drum when the same is placed on the standard.

The above-described newly-designed box 25 can also be used for buttons, trinkets, and other articles which are usually kept in small boxes, &c., on a lady's dressing-table. The puff can be secured to the under side of the cover, if desired.

I claim—

1. The herein-described newly-designed box, consisting of a box made in the shape of a kettle-drum, substantially as set forth. 30
2. The herein-described newly-designed box, consisting of a box made in the shape of a kettle-drum, and having a cover made in representation of the head of the drum, substantially as set forth. 35
3. The herein-described design for a box, consisting of a box made in representation of a kettle-drum, having drumsticks on the head, substantially as set forth. 40
4. The herein-described newly-designed support for a box made in the shape of a kettle-drum, consisting of a frame having arms in which small drumsticks are held, substantially as set forth. 45
5. The herein-described newly-designed support for a box made in the shape of a kettle-drum, consisting of a frame having arms in which small drumsticks are held, the head ends of which drumsticks are crossed, substantially as set forth. 50

WILLIAM H. BROWNELL.
